FLANGING MACHINE

Edward V. Crane and Karl A. Kuhn, Brooklyn, N. Y., assignors to E. W. Bliss Company, Brooklyn, N. Y., a corporation of Delaware

Application July 21, 1942, Serial No. 451,750

4 Claims. (Cl. 153—21)

1

The present invention relates to container making machinery and, more particularly, to a flanging machine for use in flanging the ends of metal can bodies.

Machines of this general type are old and well known and serve the functions of expanding or flaring the ends of a can body prior to the operation of securing the ends of the can. High speed production is an essential in machines of this character. The operation of the machines heretofore used has resulted in difficulty in preventing damage to the cylindrical can bodies as they are rapidly fed to and through the machine. It will be readily apparent that these bodies, consisting of cylinders of unsupported sheet metal, may be very rapidly knocked out of round as they are fed through a magazine into the machine.

In the flanging operation itself there has been difficulty, due to a tendency of the flanged end to partially resume the form it had prior to flanging. In other words, the metal was not properly set at the flange. Another disadvantage of the flanging machines hitherto in use consists in the necessity of providing heavy frames and reinforcing parts for counteracting the forming stresses of the flanging operation. The weight of the machine is thereby increased to a degree that affects the strength of the machine parts. Furthermore, with machines as heretofore constructed it has been inconvenient and difficult to adapt the same to handling cans of different sizes.

The general object of this invention has been to provide a flanging machine which overcomes the disadvantages heretofore present in machines of this character. A novel frame construction has been embodied in the machine according to the invention, in which integral tension load carrying members of the frame take up the resistance of the can flanging movement of each head, thereby eliminating objectionable bending of the main shaft of the machine with its resultant right-angle bending forces on the shaft supporting frame. It is another object of the invention to provide a frame construction by which the load may be applied to the parts during the flanging operation in a straight line, as contrasted with an offset manner, thus permitting the working thrusts to be delivered to the integral reinforcing members.

Still another object of the invention has been to provide a manner of feeding the can bodies to the machine to prevent their being knocked out of round due to bouncing in the magazine, occasioned by the speed of feeding.

2

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various means in which the principle of the invention may be used.

10 In said annexed drawings:

Fig. 1 shows a front view of the machine;

Fig. 2 shows a side elevation on a slightly larger scale, some parts being shown in section;

Fig. 2^a is a perspective view of a portion of the machine frame;

Fig. 3 is a side view in section, on a still larger scale with the hand wheel and top portion removed;

Fig. 4 is an elevation partly in section on line 20 4—4 of Fig. 3;

Fig. 5 is a section on line 5—5 of Fig. 3 which illustrates the adjusting mechanism; and

Fig. 6 is a section on line 6—6 of Fig. 4 showing the star wheel and the flanging heads.

25 Referring to Fig. 1, reference numeral 11 designates the upper part of the machine frame supported by a base 12 built in the form of a pedestal which is adapted to house a motor 14. A door 16 in the front wall of the frame gives access to the flanging mechanism proper, later to be described. Two elongated slots 17 are provided on one side of the machine by which adjustment of 30 cams for controlling the flanging mechanism is achieved, handles 18 being part of the adjusting mechanism just mentioned. This mechanism will be described below with reference to Fig. 5. A hand wheel 20 and a locking handle 21 therefore are likewise part of the adjusting mechanism; these members are shown on the left-hand side 35 of the machine frame, mounted in a cover 22.

40 Fig. 2 illustrates in a general way the set-up of the machine as seen from the left-hand side. The machine comprises an upper chute 25 for the delivery of can bodies from another operating station, where the can bodies have been prepared for the flanging operation. The chute 25, mounted on the upper part of the machine frame, consists of two plates 26 carried on said frame and attached thereto by connecting rods 28 and 29. 45 Secured to each of the plates 26 are an upper guideway 30 and lower guideway 31 mounted on said plates by means of bolts 33. The chute 25 has a straight upper portion and is curved toward the bottom, a feature which helps to eliminate jerks in the reception of can bodies arriving at 50 55

the flanging station. The bolts 33 are slidably mounted in slots 34 to 38 arranged at right angles with respect to the line of travel of the can bodies. The slots are of increased length toward the bottom part of the chute. This makes the chute adaptable for adjustment to follow the exact curve needed for smooth feeding of the cans.

It is important to follow a certain formula for the center line of the curved chute portion in relationship with the size of the particular can body to provide the above mentioned smooth feeding of can bodies at the entrance to the flanging mechanism. To this end the radius of the center line of the chute is made equal to about one and a half times the diameter of the particular can body.

Below the bottom end of the chute 25 two star wheels 40 are mounted in the center of the machine on a shaft 41. These star wheels serve to receive the incoming can bodies and to feed them through the flanging mechanism. To insure the smoothness of feeding mentioned above it is necessary to arrange the pick-up position of the pockets formed by the arms *a* of the star wheels to coincide with the discharge from the feed chute as is shown in the drawings. An important feature of the invention has been the provision of a particular path of travel for the can bodies as they are fed to the flanger. Thus the can bodies pass in a smoothly curved continuous path down the chute and into the path of the star wheels. The line of travel of the cans along the chute path meets the circular path of the star wheel at a tangent. Thus jerks and bumping in feeding are eliminated as the feed path is continuous and smooth.

In order to be able to use this flanging mechanism for cans of different diameters the width of the chute is varied in accord with the can diameter, the aforementioned ratio being retained as to diameters. Similarly, new starwheels are used providing pockets to correspond with the diameter of the can to be fed. It will of course be understood that the ratios 1:1.5, as given above need not be followed too closely but that satisfactory reception of can bodies may also be obtained if the value is altered for about 25% on the high or low side.

As shown in the embodiment illustrated by the drawings, each starwheel 40 has four arms *a*, but it may have six or more arms if it is desired or convenient. The starwheels are shaped to receive the can bodies *c* as they are delivered down the chute 25 and to carry them to the operating station proper where they are flanged, whereupon they are moved on to a lower chute and fed out of the machine in any desired manner. The lower chute consists in a pair of inclined rails 44 which are mounted by means of bolts 48 in slots 45, 46 to plates 26 and may be conveniently raised or lowered therein.

A unitary frame is provided which includes spaced, parallel members 23 and 24 and end walls 53 and 83. The parts of the frame designated by 23 and 24 are of reinforced construction and these parts are designed for taking up the thrust load of the mechanism during the flanging operation. Fig. 2^a particularly shows the reinforced frame portions 23 and 24, which, as mentioned above, are designed to relieve the main shaft from excessive stress thereby eliminating right-angle bending actions on the shaft supporting portion of the frame.

The driving connections and parts of the flanging members are shown in Fig. 4. This figure

shows the machine consisting of two halves, which are on the whole symmetrically built and equipped by the same working parts; there is, however, a common drive for both sides of the machine housed on the right-hand side, which is the stationary side, whereas the left-hand side is adjustable, as will be more fully explained later on.

The drive originating from the action of motor 12 is transmitted by belting to a pulley 50 mounted on a stub shaft 51 which is supported in sleeve bearings 52 carried in a casting 53, which forms part of the machine frame. Secured to shaft 51 and rotating therewith is a pinion 55 which meshes with a ring gear 56 that serves for driving a large rotor 57. This rotor is connected to the ring gear 56 by means of bolts 58.

Keyed at 49 to the rotor 57 so as to rotate therewith is the central shaft 41 which extends across the machine and is keyed at 49' to a second rotor 57'. It will be seen that the shaft 41, driven on the right-hand side of the machine by the rotor 57, drives the rotor 57' and other driven parts on the left-hand side of the machine.

Both rotors 57 and 57' are of substantially identical construction, they are built so as to house the plungers of the flanging members, as well as the cams and cam followers which serve as operating means for reciprocating the flanging members.

The flanging members comprise a plunger 61 with a plunger head 62 mounted thereon so as to be adjustable for fine adjustment, by means of a screw 63 whereas the adjustment of the whole flanging mechanism for cans of different sizes is made by a separate mechanism arranged on the left-hand side of the machine and illustrated in Fig. 5. A long screw bolt 65 serves for connecting the plunger head 62 to plunger 61 for holding the parts against displacement during the flanging action. The head 62 bears against a thrust plate 64 which has a rim forming portion 66 laterally enclosing part of the head, the rim being formed with a flat end face 67 receiving the can ends and imparting thereto a final bend. The plunger heads are, moreover, provided with a beveled face 68 which is stepped at 69. These faces serve for gradually bending the ends of cans to be flanged before they receive the final flange forming bend by being thrust against face 67 above mentioned. The plunger heads 62' on the left-hand side of the mechanism are not adjustably mounted, but are rigidly secured to their plungers 61' by screw bolts 65'.

The four plungers of the flanging mechanism are reciprocated by cam action in timed relationship with the rotation of the starwheels. The flanging position is shown on top, the inactive position on the bottom of Fig. 4. Since the mechanism for reciprocating the flanging members is of known construction it need not be here described.

On each side of the machine, as mentioned before, a starwheel 40 is keyed to the central shaft 41 and bolted as at 80 (Fig. 6) to a flange 81 of the rotor 57. In this figure interconnecting reinforcing webs 82 are also shown which surround the bearings supporting the four plungers 61.

Referring once more to Fig. 4, the left-hand side of the machine, carries a casting forming a sub-frame 79, which is movable on the main frame. This sub-frame supports the cams (as shown in Fig. 5) which are, therefore, adjustable together with said sub-frame. This makes the machine adaptable for flanging cans of wide-

ly differing sizes. The range of adjustability is indicated by the length of slots 17.

The means which serve for adjustment, shown in Fig. 5, comprise the hand wheel 20 which is carried on a shaft 90 that is on one end supported by a casting 83 forming part of the machine frame, at the other end mounted in a sleeve 91 having an externally threaded portion 92. The latter is threadingly engaged in a boss of the cover 22. Sleeve 91 has a flanged end 91^a which is provided with a threaded bore for engagement with the threaded end 19 of the handle 21.

Shaft 90 is operatively connected to a pinion 93 which intermeshes on either side with gears 94 and 94^a respectively. These two gears are mounted on sleeves 101 which are threaded both internally and externally, one being a right-hand and the other a left-hand thread, and the pitch of the thread being different. As a special example we may mention that the pitch of the external thread may be $4\frac{1}{2}$ to the inch, the pitch of the internal thread 7 to the inch. Threadingly received within sleeves 101 are another pair of sleeves 99 which are supported by shafts 95 and secured to a cam unit 75', 76' by an annular member 98 welded to said sleeves and screwed to the cams as at 100. In the cam unit one cam serves to control the flanging stroke, and another, not shown, controls the return stroke. Shafts 95 extend from cover 22, to which they are connected by bolts 96 and nuts 97, through frame 83 into the cam unit 75', 76'. The arrangement of the two pairs of sleeves allows of a telescopic extension or retraction of the sleeves with respect to each other, thereby making the range of adjustment considerable without the use of excessively long sleeves. The position shown in full lines in Fig. 5 is for the largest size of cans which may be handled by the machine. By moving the cams toward the right-hand side the distance between the plunger heads 62, 62' will become smaller and thereby the mechanism is adjusted to cans of shorter lengths.

The cover 22 is bolted to casting 83 by means of bolts 106. Behind the casting 83, which is part of the machine frame, the movable casting 79 is shown in dotted lines; this latter casting is secured to cams 75', 76' by bolts 78', and forms, as mentioned above, an adjustable unit with said cams.

In the construction of the flanging mechanism it is an important feature that the parts carrying the stresses are all substantially in alignment, viz., in a plane approximately coinciding with the middle portion of section line 5, in Fig. 3. This accounts for the absence of any twists or cantilever action on the frame. The construction of the adjustment mechanism and the cam arrangement are very strong; the load acting on the cams in a horizontal direction is transmitted through the screws into the vertical plane of frame 83 and from there again over the horizontal frame portions to the vertical plane of the cam unit. This quasi-box construction insures the absorption of high stresses without detrimental deflections of the machine frame.

For locking the cams and the mechanism associated therewith in the desired position, a locking device is provided, parts of which have already been explained, while others are best shown in Fig. 3. The mechanism comprises elongated bolts 103 with ends 104 threadingly received in frame 79. The bolts are passed through slots 107 of casting 83 and with their other ends are mounted in members 105 of hemisphere 75

shape, which bear on bosses 108 of casting 83. Pins 109 serve for fastening the bolts 103 to members 105 which form part of the handles 18. By tightening or loosening these handles, locking or unlocking of the adjusting mechanism in a desired position is accomplished. A gib plate 110 is provided and screwed to the machine frame as at 111, on which the movable casting 79 rides while it is moving back and forth for adjustment.

For operating the adjusting mechanism, handles 18 are loosened to an extent which will relieve the pressure of members 105 on bosses 108 and allow the members to slide in slots 17. Next the shaft 90 will be unlocked by means of handles 21. Then hand wheel 20 is turned to operate pinion 93 which will actuate the gears 94 and 94^a and rotate the sleeves 101, on which these gears are mounted. The external threads of sleeves 101, which are right-hand threads, are screwed forward in casting 83, thereby moving the sleeves to the right-hand side. The inner sleeves 99 are taken along during this movement for the same distance as sleeves 101 are moved. At the same time the inner threads of sleeves 101 which are left-hand threads, turn on sleeves 99 likewise moving the same to the right-hand side. By the combined action of both threads sleeves 99 are caused to advance at a faster rate than sleeves 101. If the full extent of the threads on the sleeves is used the cams 75', 76', together with their supporting frame 79 are carried forward to the position shown in dotted lines in Fig. 5. It is however, obvious that any intermediate position between the two extremes may be taken up and the cams fixed in that position by the tightening of handles 18 and locking of shaft 90.

Before the machine is started the mechanism is adjusted for flanging cans of different lengths in the manner just described, in addition thereto fine adjustment of the plunger heads 62 by screws 63 may be desirable. The adjustment and, if necessary, exchange of the guideways 30, 31 in the delivery chute, on the other hand, will have to take care of adapting the machine for can bodies of varying diameters as indicated above. The star wheels 40 will also have to be so chosen that the pockets between the two arms will follow the contour of the can body to be treated. Finally, the size of the plunger heads 62 has to correspond to the diameter of the can bodies and several sets of plunger heads with thrust plates 64 fitted thereto will, therefore, have to be kept ready for use.

In operation motor 14 will drive the pinion 55, thereby rotating gear 56, rotor 57 and shaft 41, which in turn will drive the left-hand side of the mechanism in unison with the right-hand side thereof. Starwheels 40, turning on shaft 41, receive the can bodies delivered from chute 25 and feed them past the flanging station shown by arc B—B, where, owing to the action of cam 75 and its follower, and the action of corresponding members in the other half of the machine, plungers 61, 61' advance the heads 62, 62' and the flanges are gradually formed by bending the metal back on the stepped beveled faces 68, 69 and 68', 69', respectively, of these heads until it receives the final bends at 67, 67'. The can body then passes the station shown in the lower part of Fig. 4, where the plungers are illustrated in idle position after having been retracted by the action of return cams. The can bodies are then fed out of the mechanism through the lower chute over rails 44.

Other modes of applying the principle of our

invention may be employed instead of the one explained, change being made as regards the mechanism herein disclosed, provided the means stated by any of the following claims or the equivalent of such stated means be employed.

We therefore particularly point out and distinctly claim as our invention:

1. In a flanging machine, a frame including two spaced, parallel frame members, a rotor mounted between said frame members; a flanging member reciprocatively mounted on said rotor; means for rotating said rotor; means for actuating said flanging member during rotation of said rotor including, a cam, a frame member for supporting said cam; means for releasably securing opposite ends of said frame member to said parallel frame members, respectively, for selectively positioning said cam in the frame and compression resistant means interconnecting said cam and a fixed member of said frame, the last mentioned means being extendable and retractile and being disposed substantially on a line projected through said arc and parallel to the axis of said arc.

2. In a flanging machine, a frame; a rotor mounted on said frame; a flanging member reciprocatively mounted on said rotor; means for rotating said rotor to carry the flanging member in an arc; means for actuating said flanging member during rotation thereof through a portion of said arc including, a cam; a frame member; means for mounting said cam to said frame member including, a threaded shaft extending from one face of said cam, said frame member having an opening through which said shaft extends, the center of said opening being disposed substantially on a line projected through said portion of said arc and parallel to the axis of said arc, a sleeve internally and externally threaded and adapted to threadingly receive said shaft, said sleeve being threaded in said opening in said frame member, the pitch of the threads of said shaft and sleeve being such as to cause longitudinal movement of said shaft and sleeve in the same direction through said opening when said sleeve is rotated for adjustably positioning said cam and means for rotating said sleeve.

3. In a flanging machine, a frame; a rotor mounted on said frame; a flanging member reciprocatively mounted on said rotor; means for rotating said rotor; means for actuating said flanging member during rotation of said rotor including, a cam; a frame member; means for mounting said cam to said frame member including, a threaded shaft extending from one face of said cam, said frame member having an opening through which said shaft extends, a sleeve internally and externally threaded and adapted to threadingly receive said shaft, said sleeve being threaded in said opening in said frame member, the pitch of the threads of said shaft and sleeve being such as to cause longitudinal movement of said shaft and sleeve in the same direction through said opening when said sleeve is rotated for adjustably positioning said cam; means for rotating said sleeve; a second frame member to which said cam is secured; and means for removably clamping said second frame member to said frame throughout a portion of the frame along which said second frame member is movable as the position of the cam is changed.

4. In a flanging machine, a frame including, a frame member adapted to be moved to a plurality of positions; means for securing said frame member in said positions; a shaft journaled in said frame member; a rotor mounted on said shaft; a flanging member carried by said rotor and adapted to reciprocate relative to the rotor and carried in an arc when the rotor is rotating; means for actuating said flanging member in a direction parallel to the axis of said arc during rotation of said rotor including, a cam, said cam being secured to said frame member; and compression resistant means interconnecting said cam and a fixed member of said frame, the last mentioned means being extendable and retractile and being disposed substantially on a line projected through said arc parallel to the axis of said arc.

EDWARD V. CRANE,
KARL A. KUHN.
